Pittsburgh, Pa., a corporation of Pennsylvania

Application February 22, 1945, Serial No. 579,248

6 Claims. (Cl. 201—51)

1

This invention relates to regulators and in particular to regulators of the magnetic type.

As is well known, small alternating-current generators can be widely used in many different applications, but for satisfactory service they require small regulators which have a rugged balanced design and are contained in a single compact unit. The simplest self-contained unit regulator is that which uses an alternating-current magnet and operates directly from the alternating-current output of the generator without the use of intermediate rectifiers. In such alternating-current magnetic type of regulators, it has been found that errors occasioned by changes in frequency or by vibration caused by the sinusoidal current usually prevent the satisfactory use of alternating-current regulators forcing the user to employ a direct-current magnetic type of regulator and the accompanying equipment necessary to convert the alternating current to unidirectional current.

An object of this invention is the provision of a rugged, compact regulator of the alternating-current magnetic type.

Another object of this invention is the provision of an alternating-current magnetic type of regulator which inherently compensates for change in frequency.

A more specific object of this invention is to provide for compensating for frequency changes and vibration in an alternating-current magnetic type of regulator, the regulator being constructed as a compact unit and being capable of use in any mounted position.

Other objects of this invention will become apparent from the following description when taken in conjunction with the accompanying drawings in which:

Figure 1 is a top plan view, with the cover removed, of a regulator embodying the teachings of this invention.

Fig. 2 is a side elevational view, with parts removed, of the regulator shown in Fig. 1.

Fig. 3 is a bottom plan view of part of the regulator shown in Fig. 2 but removed from the housing.

Fig. 4 is a fragmentary end view of part of the housing mounting and terminal block of the regulator shown in Fig. 2.

Fig. 5 is a view taken along the line V—V of Fig. 4.

Fig. 6 is a diagrammatic showing of a part of the regulator.

Fig. 7 is a representation of the impedances and resistance of the apparatus shown in Fig. 6.

Fig. 8 is a diagrammatic showing of another part of the regulator.

Fig. 9 is a representation of the impedances and resistance of the part of the regulator shown in Fig. 8.

Fig. 10 is a representation of the relation of the current and voltage in the parts of the regulator shown in Figs. 6 and 8 as they co-operate, and

Fig. 11 is a schematic diagram of apparatus and circuits illustrating the regulator of this invention as used in a regulating system.

Referring to the drawings and in particular to Figs. 1 and 2 thereof, this invention is illustrated as comprising a voltage regulator 10 having a main housing 12 for containing the main movable parts thereof and an auxiliary housing 14 for containing a resistor unit, both housings being secured together and mounted on, but spaced from, a suitable base member 16.

The main housing 12 is formed of metal being drawn or otherwise formed to have integral side walls 18 and bottom 20, a removable cover 22 being disposed to enclose the cavity formed therein. The bottom 20 is provided with a centrally disposed aperture 24 through which leads may extend as described hereinafter. The upper edge of one of the side walls 18 is cut away as at 26 for accommodating certain leads referred to hereinafter and suitable inwardly extending brackets 28 are secured to the inner sides of three of the side walls at a predetermined level within the cavity. Adjacent the fourth side wall is disposed a capacitor unit 30 which is mounted on the bottom 20 as by means of the studs 32, the terminals 34 and 36 of the capacitor being insulated from, but extending through, suitable apertures in the bottom 20. The capacitor 30 extends upwardly, as viewed in Fig. 2, along the side wall to a line adjacent the upper edge of the housing 12.

The operating or movable elements of the regulator are assembled on a baffle plate 38 which is disposed to seat on the brackets 28 being secured thereto as by means of a nut and bolt assembly 40 whereby the plate 38 carrying the movable elements can readily be removed from the housing when necessary. As illustrated in Figs. 1 and 3, the baffle plate 38 is so cut as to fit around the capacitor unit 30 and to leave space between the edges of the plate 38 and the side walls to permit circulation of air within the main housing. The plate 38 is also provided with a somewhat centrally positioned aperture 42, the purpose of which will be explained hereinafter.

As viewed in Figs. 1 and 2, the plate 38 car-

ries a switching mechanism 44 on its upper surface at one side of the aperture 42. The switching mechanism illustrated comprises a plurality of long thin conducting members 46 which are insulated at one end from each other but securely clamped together in an insulating block 48 secured to the plate 38 by the screws 50, the other ends of the conducting members 46 having contact buttons or members 52 thereon and being self-biased to seat spaced apart against an angular stop member 54 which is also secured to the plate 38. A driver member 56 of insulating material, the mounting of which will be explained more fully hereinafter, is disposed to actuate the conducting members 46 in a progressive manner, a spring 58 being mounted on a bracket 60 carried by the plate 38 for biasing the driver member 56 against the conducting members.

The operating mechanism for actuating the driver member 56 is more clearly shown in Fig. 3 and is mounted on the under side of the plate 38 as illustrated in Fig. 2. As illustrated, the operating mechanism comprises two positionally opposed electromagnets 62 and 64 which are secured to the plate 38 by brackets 66 and 68, respectively, the electromagnets being structurally similar and preferably having substantially identical electrical characteristics. The electromagnets 62 and 64 comprise the windings 70 and 72, respectively, and the movable core members 74 and 76, respectively. As illustrated, the electromagnets are carried on the under side of the plate 38 in spaced relation and in the reverse direction to each other so that when energized the core members 74 and 76 tend to move in opposite directions in substantially parallel pairs. In order to prevent stray fluxes, disk members 78 are disposed at each end of the electromagnets.

As it is proposed to simultaneously energize the electromagnets 62 and 64, the core members 74 and 76 are coupled by a connecting arm 80 which has angular end portions secured to the core members. The central section of the connecting arm 80 is secured to a vertical arm 82 as viewed in Fig. 2 by the rivets 84 near the lower end of the vertical arm 82, the upper end of which projects through the aperture 42 and is secured by the screw 86 to the driver member 56.

In order to pivotally support the connecting arm 80 and consequently the driver member 56, a downwardly projecting bracket 88 is secured to the plate 38 by screws 90. Spaced apart on each side of the connecting arm 80 are leaf springs 92 and 94, each of which has one end thereof secured to the bracket 88 by rivets 96, the other ends of the leaf springs 92 and 94 being secured to the arm 82 by the rivets 98 and 100, respectively. In order to prevent sharp bending of the leaf springs 92 and 94, relatively stiff leaf members 102 and 104 are disposed adjacent the opposite sides of each of the spring members, the stiff leaf members 102 and 104 having a turned end which is positioned near the portion of the springs in which the bending takes place.

In order to balance the pull of electromagnets 62 and 64 and the bias of the self-biased conducting members 46 to maintain the driver member 56 in a given position in accordance with the energization of the electromagnets 62 and 64, a biasing spring 106 is disposed with its one end secured to an adjustable screw member 108 carried by the end of the connecting arm 80 secured to the core member of electromagnet 64, the other end of the biasing spring 106 being secured through a bolt 110 to an end of a bimetal leaf 112, the other end

of which is secured to the downwardly projecting bracket 114 carried by the plate 38. The bimetal leaf 112 affords temperature compensation for the operating mechanism by varying the tension of the biasing spring 106 in accordance with changes in temperature.

With the electromagnets 62 and 64 secured to the plate 38 as described, and the driver member 56 pivotally carried by the connecting arm 80 to 10 actuate the switching mechanism 44 carried on the other side of the plate 38, the assembled operating mechanism is readily positioned in the housing with the leads 116 and 118 of electromagnet 62 and leads 120 and 122 of electromagnet 64 extending outwardly through the aperture in the base of the housing. Leads 124 constituting an extension of the conducting leaf spring members 46 and which are insulated from each other by suitable strips 126 of insulating material extend outwardly through the cut away section 26 in the side wall.

As illustrated in Figs. 1 and 2, the auxiliary housing 14 is carried by one of the side walls of housing 12 and encloses a pile resistor unit 128. 20 In order to support the pile resistor unit 128, end plates 130 and 132 formed of substantially U-shaped channel members are positioned facing each other, one of the flanges of each of the plates 130 and 132 terminating in an aligned downwardly extending leg 134, respectively, which are secured to a tie bar 138 by recessed screws 140 to maintain them in spaced relation. Extending through the end plates 130 and 132 are supporting tie bolts 142, 144, 146 and 148 which are so spaced as to hold the disks of the resistor unit 128 in assembled relation, it being noted that the leads 124 extend downwardly in contact relation between the disks of the resistor unit.

Pressure plates 150 and 152 are disposed at opposite ends of the stack of disks and are held in pressure applying position by the rivets 154 and 156, respectively, the heads of the rivets seating in grooved out depressions in the faces of the pressure plates, the tie bolts 142, 144, 146 and 148 also 30 functioning to aid in positioning the pressure plates. A tie bar 158 also extends between the other flanges of the end plates 130 and 132 being welded thereto and aiding in supporting the stack of disks of the resistor unit 128. The housing 14 which is open at the bottom and back, and is 40 preferably of a screen material, is positioned over the assembled resistor unit and removably secured to the outer flanges of end plates 130 and 132 by screws 160.

In order to secure the assembled resistor unit to the main housing 12, a bar 162 is positionally welded to the side wall of the housing 12 and the tie bar 138 is secured thereto by spaced screws 164 as more clearly shown in Fig. 4. In this position the leads 166 and 168 at the ends of the resistor unit 128, and which are secured to the leads 124 at the ends of the stack as viewed in Figs. 1 and 2, depend through the open bottom of the housing 14.

The housings 12 and 14 with the operating mechanism therein as described are resiliently mounted on the base member 16 by means of four spaced studs 170 extending through the base of the main housing 12 and resilient bushings 172 disposed between the housing 12 and the base member 16. The resilient bushings 172 are of sufficient size to permit the leads from the electromagnets 62 and 64 and lead 174 to the terminal 36 of the capacitor to extend between the bottom of the main housing 12 and the base 16

to a terminal block 176 mounted at the end of the base beneath the housing 14.

The terminal block 176 consists of a strip 178 of insulating material carrying four spaced terminals 180, 182, 184, and 186 suitably riveted thereto for receiving the leads of the regulator. As shown in the schematic diagram, Fig. 11, the resistor leads 166 and 168 are secured to the outer terminals 186 and 180, respectively, whereas leads 174 to the capacitor 30 and lead 122 to electromagnet 64 are connected to the terminal 184, and lead 120 to electromagnet 64 and lead 118 to electromagnet 62 are connected to the remaining terminal 182, the lead 116 of electromagnet 62 being connected to the other terminal of the capacitor 30 whereby the capacitor 30 and the winding of electromagnet 62 are connected in series circuit relation with each other and the series connected elements are connected in parallel circuit relation with the other electromagnet 64.

The insulating strip 178 carrying the terminals extends across the end of the regulator and is maintained in an angular position on spaced supports. The supports are formed of a hollow insulating post 190 and a base member 192 each having a complementary angular surface for seating on opposite sides of the base member 16, the strip 178, post 190 and member 192 being held in assembled relation by screws 194, the end of which is in threaded engagement with the member 192.

Referring to Fig. 11, the regulator 10 is illustrated as connected in a system for regulating the voltage of an alternating-current generator 196. As illustrated, the generator 196 consists of an armature winding 198 connected by the circuit breaker 200 to deliver power to a polyphase system represented by conductors 202, 204 and 206, and a field winding 208 disposed to be energized by an exciter 210, the generator 196 and exciter 210 being disposed to be driven by a motor 212. The exciter 210 is of conventional design having an armature winding 214 connected to supply the field winding 208 and a self-excited field winding 216 having the resistor unit 128 of the regulator 10 connected in circuit relation thereto for controlling the excitation of the exciter. The terminals 182 and 184 of the regulator 10 are connected to the terminals of the secondary winding of a potential transformer 218, the primary winding of which is connected across a phase of the conductors supplied by generator 196 whereby the opposed electromagnet 62 and 64 of the regulator 10 are disposed to be simultaneously energized and any variation in the voltage across the conductors supplied by the generator 196 has a direct effect on the operation of the regulator.

In order to better understand the operation of the regulator 10 when a variation in the alternating-current voltage occurs, reference may be had to Figs. 6 through 10. Fig. 6 is a representation of electromagnet 64 connected to be supplied from the alternating-current circuit and is shown to comprise the resistance R of winding 72 and the reactance X_L of the winding. Thus the impedance Z_1 of the electromagnet 64 is as shown in Fig. 7 since

$$Z_1 = \sqrt{(R)^2 + (X_L)^2} \quad (1)$$

The total current I_1 in the winding of electromagnet 64 is then equal to the voltage E_1 supplied to terminals 182 and 184 divided by the impedance Z_1 . The flux will be proportional to the

current I_1 and remains constant with constant voltage and constant frequency of sinusoidal wave form.

However, as is well known, the frequency changes when the speed of the prime mover changes due to load changes. Thus, since the reactance X_L is a function of $2\pi fL$, the reactance X_L will increase when the frequency f increases and will decrease with a decrease in the frequency. Then from Equation 1 it is seen that the impedance Z_1 will increase with an increase in the frequency with the result that with constant voltage E_1 across terminals 182 and 184 the current I_1 will decrease and consequently the flux and pull of electromagnet 64 will decrease.

As stated hereinbefore, the electromagnets 62 and 64 are structurally similar and preferably have substantially identical electrical characteristics, but are mounted in opposed relation. As opposed to electromagnet 64, the electromagnet 62 is also connected in series with the capacitor 30 so that the circuit for the electromagnet 62 may be illustrated as in Fig. 8 being composed of the inductive reactance X_L of winding 10, the resistance R of the winding, and the capacitive reactance X_C . In practice, the capacitive reactance X_C is generally proportioned so that it is equal to two times the value of the inductive reactance X_L and as the impedance Z_2 of the circuit of electromagnet 62 may be given as

$$Z_2 = \sqrt{(R)^2 + (X_L - X_C)^2} \quad (2)$$

the impedance Z_2 may be illustrated as in Fig. 9 of the drawing in which the combined reactance $X = X_C - X_L$ or a capacitive reactance.

As the capacitive reactance X is a function of

$$\frac{1}{2\pi fC}$$

it will be appreciated that the capacitive reactance will increase with a decrease in frequency or decrease with an increase in frequency and from Equation 2, it follows that the impedance Z_2 will then decrease with a decrease in frequency and that the flux and resulting magnetic pull of electromagnet 62 will increase. Thus where the reactance X_L and the resistance R of the windings of electromagnets 62 and 64 are equal, by proportioning the capacitor to have a reactance equal to two times the value of the inductive reactance of one of the windings, the pull on the one electromagnet is decreased an amount equal to the increase in pull on the other electromagnet when a change in frequency is encountered, whereby the net result is that the total magnetic pull remains unchanged varying only with a change in the voltage of the machine to be regulated. Thus the regulator 10 is unaffected by changes in frequency of the alternating-current supply.

From Figs. 7 and 9, it is seen that the impedance Z_1 and the impedance Z_2 are 90° apart. Since the current I_1 is in phase with resistance R and is 45° out of phase with the voltage E_1 , and the current I_2 in the winding of electromagnet 62 is 45° out of phase in the opposite direction from the voltage E_2 applied to the regulator, it is seen from Fig. 10 that the currents I_1 and I_2 are 90° apart as the voltages E_1 and E_2 are one and the same. As the flux wave in an alternating current magnet is sinusoidal, the wave or force pulsates from zero to maximum two times per cycle on each electromagnet. Since, as shown in Fig. 10, the currents I_1 and I_2 are out of phase by an angle

of 90°, the flux will also be shifted 90° and the force will pulsate on the connecting arm 80 between the electromagnet 62 and 64 with the equivalent of four times per cycle. By properly balancing the pull of the main spring 106 for the mass of the moving parts of the regulator, the vibration is reduced to a minimum to give a required sensitivity to the regulator. In some cases it is desirable to add weights (not shown) to the connecting arm to increase the mass and thereby effect damping to permit an increase in the frequency range and still maintain a sensitive operation.

With the foregoing description, the operation of the regulator 10 is apparent. For example, in the system illustrated in Fig. 11 assume that the motor 212 is driving the exciter 210 and generator 196 to supply a given load at a constant voltage. Under such circumstances, the electromagnets 62 and 64 are so energized that a number of the leaves 46 are actuated away from the sloped stop 54 to shunt a number of sections of the resistor unit 128 from the field winding circuit of the exciter 210.

If, for any reason, the load should change such as to cause a decrease in the voltage impressed on transformer 218, the windings of electromagnets 62 and 64 are deenergized proportionally whereby the main spring 106 actuates the connecting arm 80 about its pivot to effect a movement of the driver member 56 to bias additional leaves 46 away from the stop 54 to shunt additional sections of the resistor unit 128 and thereby increase the excitation of the exciter 210 to effect an increase in the excitation of the generator 196 to increase the voltage across the conductors to the predetermined constant voltage.

If, on the other hand, the change in voltage impressed on the transformer 218 is an increase, then the energization of the windings of electromagnets 62 and 64 is an increase to effect a movement of the connecting arm 80 about its pivot to actuate the driver member 56 to release additional leaves 46 and connect additional sections of the resistor unit 128 in circuit with the field winding of exciter 210 and thereby decrease the excitation of the exciter. Such decrease in the excitation of the exciter 210 effects a decrease in the excitation of generator 196 to reduce the voltage across the conductors to the predetermined constant value.

From the description given hereinbefore with respect to the capacitor 30 and the proportioning thereof relative to the inductive reactance of the winding with which it is connected in series circuit, it is apparent that the regulator 10 is unaffected by any change in frequency of the alternating-current voltage supplying the regulator. Although, as stated hereinbefore, it is preferred to proportion the capacitive reactance of the capacitor 30 to two times the value of the inductive reactance of the winding of the electromagnet, it is, of course, understood that variations in the proportioning may be had where it is desired to compensate for a drop in speed of the prime mover.

For example, the capacitor 30 can be so proportioned that the impedance Z_2 is so altered that there is a slight unbalance in the total pull on the connecting arm to make up for the droop in speed and consequently the change in frequency when load is applied. This droop in speed is characteristic of the machine or generator when load is applied it being noted that the speed also

increases somewhat when the load is removed. Small machines usually have a permissible droop of plus or minus 3%. The regulator described can therefore be made to compensate for the voltage which results in droop and can even be made to compensate more than required for flat voltage regulation and thus give a rise in voltage with increased load as required in some applications by correctly proportioning the capacitor 30. Thus overcompensation may be had by proportioning the capacitive reactance of the capacitor 30 so that it is greater than twice the value of the inductive reactance of the electromagnet.

15 The regulator 10 is compact in size but rugged in construction. It is very sensitive having an exceedingly smooth operation by reason of increasing the pulsations applied to the connecting arm between the opposed electromagnets. As the regulator can be energized directly from an alternating-current source without the use of intermediate rectifiers, the simplification of apparatus required is apparent. Because of its ruggedness, it can be used in any position without affecting its operation.

I claim as my invention:

1. In a voltage regulator for an alternating-current dynamoelectric machine having a variable frequency, in combination, contact members disposed for movement to and from contact making positions, a driver member disposed to be actuated to effect the movement of the contact members, a pair of electromagnets having substantially identical electrical characteristics, each of the electromagnets having a winding and a core member, the windings being connected in parallel circuit relation with each other disposed to be simultaneously and directly energized by alternating current in accordance with the operation of the dynamoelectric machine, the electromagnets being disposed in spaced relation and positioned in the reverse direction to each other whereby the core members move in substantially parallel paths but in opposite directions when the windings are simultaneously energized, a connecting arm pivotally disposed between and connected to the spaced core members, the connecting arm also being connected to the driver member to effect a movement thereof as the arm is pivotally moved, and a capacitor connected in series circuit with only one of the windings, each of the winding circuits comprising a non-resonant circuit, the capacitor functioning upon a change in frequency of the dynamoelectric machine to modify the effective impedance of the one winding circuit whereby the change in the magnetic pull of the one winding occasioned by the change in frequency is in opposition to the change in the magnetic pull of the other winding occasioned by the change in frequency.

2. In a voltage regulator for an alternating-current dynamoelectric machine having a variable frequency, in combination, an adjustable resistor, means disposed for movement to adjust the resistor, a pair of electromagnets having substantially identical electrical characteristics, each of the electromagnets having a winding and a core member, the windings being connected in parallel circuit relation with each other disposed to be simultaneously and directly energized by alternating current in accordance with the operation of the dynamoelectric machine, the electromagnets being disposed in spaced relation and positioned in the reverse direction to each other whereby the core members move in substantially

parallel paths but in opposite directions when the windings are simultaneously energized, a connecting arm pivotally disposed between and connected to the core members, the connecting arm also being connected to the adjusting means to effect an adjustment of the resistor as the arm is moved, and a capacitor connected in series circuit with only one of the windings, each of the winding circuits comprising a non-resonant circuit, the capacitor functioning upon a change in frequency of the dynamoelectric machine to modify the effective impedance of the one winding circuit whereby the change in the magnetic pull of the one winding occasioned by the change in frequency is in opposition to the change in the magnetic pull of the other winding occasioned by the change in frequency.

3. In a voltage regulator for an alternating-current dynamoelectric machine having a variable frequency, in combination, a plurality of contact members disposed for movement to and from contact making positions, a driver member disposed to be actuated to effect the movement of the contact members, a pair of electromagnets having substantially identical characteristics, each of the electromagnets having a winding and a core member, the windings being connected in parallel circuit relation with each other disposed to be simultaneously and directly energized by alternating current in accordance with the operation of the dynamo-electric machine, the electromagnets being disposed in spaced relation and positioned in the reverse direction to each other whereby the core members move in parallel paths but in opposite directions when the windings are simultaneously energized, a connecting arm pivotally disposed between and connecting the core members, the connect-arm also being connected to the driver member to effect a movement thereof as the arm is moved, and a capacitor connected in series circuit with only one of the windings, each of the winding circuits comprising a non-resonant circuit, the windings having the capacitor in circuit with the one winding co-operating upon a change in frequency of the dynamoelectric machine to maintain a substantially constant total magnetic pull on the core members variable only with changes in the voltage of the dynamoelectric machine.

4. In a voltage regulator for an alternating-current dynamoelectric machine having a variable frequency, in combination, an adjustable resistor, means disposed for movement to adjust the resistor, a pair of electromagnets having substantially identical electrical characteristics, each of the electromagnets having a winding and a core member, the windings being connected in parallel circuit relation with each other disposed to be simultaneously and directly energized by alternating current in accordance with the operation of the dynamoelectric machine, the electromagnets being disposed in spaced relation and positioned in the reverse direction to each other whereby the core members move in parallel paths but in opposite directions when the windings are simultaneously energized, a connecting arm pivotally disposed between and connected to the core members, the connecting arm also being connected to the adjusting means to effect an adjustment of the resistor as the arm is moved, and a capacitor connected in series circuit with only one of the windings, each of the winding circuits comprising a non-resonant circuit, the windings with the capacitor in series circuit with the one winding co-operating upon a change in frequency

of the dynamoelectric machine to maintain a substantially constant total magnetic pull on the core members variable only with changes in the voltage of the dynamoelectric machine.

5. In a voltage regulator for an alternating-current dynamoelectric machine having a variable frequency, in combination, a plurality of contact members disposed for movement to and from contact making positions, a driver member disposed to be actuated to effect the movement of the contact members, a pair of electromagnets having substantially identical characteristics, each of the electromagnets having a winding and a core member, the windings having substantially equal values of inductive reactance and being connected in parallel circuit relation with each other, the windings being disposed to be simultaneously and directly energized by alternating current in accordance with the operation of the dynamoelectric machine, the electromagnets being disposed in spaced relation and positioned in the reverse directions to each other whereby the core members move in parallel paths but in opposite directions when the windings are simultaneously energized, a connecting arm pivotally disposed between and connecting the core members, the connecting arm also being connected to the driver member to effect a movement thereof as the arm is moved, and a capacitor connected in series circuit with only one of the windings, the capacitor having a capacitive reactance at a predetermined frequency of the dynamoelectric machine equal to two times the inductive reactance of the winding with which it is connected in series circuit, the winding having the capacitor in circuit therewith co-operating with the other winding upon a change in frequency of the dynamoelectric machine from the predetermined frequency to maintain a substantially constant total magnetic pull on the core members variable only with changes in the voltage of the dynamoelectric machine.

6. In a voltage regulator for an alternating-current dynamoelectric machine having a variable frequency, in combination, an adjustable resistor, means disposed for movement to adjust the resistor, a pair of electromagnets having substantially identical electrical characteristics, each of the electromagnets having a winding and a core member, the windings having substantially equal values of inductive reactance and being connected in parallel circuit relation with each other disposed to be simultaneously and directly energized by alternating current in accordance with the operation of the dynamoelectric machine, the electromagnets being disposed in spaced relation and positioned in the reverse direction to each other whereby the core members move in parallel paths but in opposite directions when the windings are simultaneously energized, a connecting arm pivotally disposed between and connected to the core members, the connecting arm also being connected to the adjusting means to effect an adjustment of the resistor as the arm is moved, and a capacitor connected in series circuit with only one of the windings, the capacitor having a capacitive reactance at a predetermined frequency of the dynamoelectric machine equal to two times the inductive reactance of the winding with which it is connected in series circuit, the winding with the capacitor in series circuit therewith cooperating with the other winding upon a change in frequency of the dynamoelectric machine from the predetermined frequency to maintain a substantially constant total magnetic

pull on the core members variable only with changes in the voltage of the dynamoelectric machine.
